SIZE ADJUSTER FOR DRESSES

Harry D. Lytle, New York, N. Y.

Application January 14, 1937, Serial No. 120,593

4 Claims. (Cl. 2—243)

This invention relates to a size adjuster for dresses and other garments and more particularly relates to a gauge strip temporarily applied to a dress by a manufacturer in cooperating relation to seams thereof so that the seams can be accurately let out to increase the size of the garment.

At the present time, dresses are made in a number of sizes and a merchant must purchase 10 dresses of different sizes in order that a dress of the proper size may be sold to a customer. This makes it necessary for the merchant to carry a large stock of dresses which represent a large investment and it often happens that sale of a 15 dress is lost due to the fact that the merchant does not have a dress of the proper size in the pattern selected by a customer.

Therefore, one object of the invention is to provide a dress having a size adjuster associated 20 therewith which permits the dress to be very easily altered and fit the customer. It will thus be seen that the merchant can purchase dresses of an approximate size and easily alter them in case the made up size is too small for the customer.

Another object of the invention is to so form the size adjuster that it may be carried by the hem for the bottom of a dress in such position that it extends along a side seam in bridging relation to hems of the side seam, gauge markings being provided upon the size adjuster in transverse spaced relation to each other so that if the dress as made is too small, companion gauge markings and portions of the hems can be 35 brought together and the hems accurately seamed to each other, the original seam being then removed so that the dress will be increased one or more sizes as necessary to provide the correct fit.

Still another object of the invention resides 40 in providing a device which is simple and durable in construction, inexpensive to manufacture and one which will be very efficient in operation and application to use.

With these and numerous other objects in view, my invention consists in the novel features of construction, combination and arrangement of parts as will be hereinafter referred to and more 45 particularly pointed out in the specification and claims.

The invention is illustrated in the accompanying drawing wherein:

Figure 1 is a view in elevation of a fragment 55 of a dress or other garment showing the improved

size adjuster as it appears when initially applied thereto;

Figure 2 is a sectional view taken along the line 2—2 of Figure 1;

Figure 3 is a view similar to Figure 1 showing 5 the size adjuster associated with a garment of an intermediate size;

Figure 4 is a sectional view taken along the line 4—4 of Figure 3;

Figure 5 is a view similar to Figures 1 and 3 10 showing the size adjuster associated with a large size garment;

Figure 6 is a sectional view taken along the line 6—6 of Figure 5;

Figure 7 is a perspective view showing a portion 15 of the garment in longitudinal section at one side of the seam; and

Figure 8 is a perspective view of the size adjuster.

The dress or other garment is formed of sections 20 which are sewed to each other to provide seams at sides of the garment, it being understood that the dress may be formed with other seams if the style of dress calls for them. The side seams have the size adjusters associated 25 with them as these seams are to be let out in case the garment is too small for the customer. When the garment is cut the sections are of such dimensions that when side edge portions of the sections 1 and 2 are sewed together as shown at 30 3 to form a seam, wide hems 4 and 5 will be provided at opposite sides of the seam. A binding 6 is sewed along the lower edges of the sections and when the lower portions of the sections are turned up to form a lower hem 7, the upper edge 35 of the binding is basted to the sections as shown at 8 in order that it will be temporarily secured and the hem may be adjusted in case the dress is not the right length.

The size adjuster 9 consists of a strip of linen 40 or other fabric which can be easily folded and will not detract from the appearance of the dress or prevent it from being washed and ironed in case the size adjuster is left upon the garment for guidance of a customer who purchases a garment 45 for a growing child and may wish to increase the size thereof as the child grows. The size adjuster or strip 9 is of rectangular outline as shown in Figure 8 and is sewed to the binding 6 by a line of stitching 10 in such position that it extends upwardly from the lower hem 7 along the seam 3 in overlying and bridging relation to the side hems 4 and 5. Side edges of the strip or size adjuster are in close proximity to edges of the hems and the dot-and-dash line 11 at the transverse center 50 55

of the strip is disposed in alignment with the seam 3. At equal distances from opposite sides of the center line 11 are provided companion indicator lines 12 and 13 which are correspondingly marked 5 as shown at 14 and 15 to designate increases in size of the garment by one or two sizes. The upper end of the strip is stitched to the hems as shown at 16 to hold it in place flat against the hems.

10 When a dress or other garment provided with size adjusters is tried on by a customer and it is found to be too small, the fitter can very easily increase the size of the garment by folding the size adjusters associated with the side seams 15 along the center lines 11 until either the gauge lines 12 or 13 are brought together and then sewing the hems to each other to form a new seam, after which the original seam can be removed. An accurate adjustment will thus be 20 made and the garment increased one or two sizes so that it will fit the customer. Instead of the manufacturer making the garment in its smallest size, the garment can be made an intermediate size as shown in Figures 3 and 4 or it may be made 25 its largest size as shown in Figures 5 and 6. When the initial size is the intermediate size shown in Figures 3 and 4, the garment can be either taken in or let out by using the gauge lines as guides and when the garment is initially made its largest size 30 as shown in Figures 5 and 6, the garment may be taken in by using the gauge lines as guides to determine the correct width of seam to provide a garment of the correct size. After the garment has been adjusted to produce the correct size, the 35 size adjuster may be removed, or it can be left in place so that when the garment is bought for a growing child, it can be later on altered as the child grows.

While in the present invention, I have disclosed 40 the linen strip, constituting the size adjuster, as being sewed to the inside of the hem, it is to be understood that the linen strip may equally as well be attached to the outside of the hem at the side seam.

45 It will thus be seen that a merchant instead of purchasing garments of a popular pattern in all sizes need only purchase a stock of garments of approximate sizes and can very easily alter the garments to obtain a correct fit as they are 50 bought by customers.

From the foregoing description of the construction of my improved device, the operation thereof and the method of applying the same to use will be readily understood. It will be seen that 55 I have provided a simple, inexpensive and efficient means for carrying out the objects of the invention and while I have particularly described

the elements best adapted to perform the functions set forth, it is obvious that various changes in form, proportion and in the minor details of construction may be resorted to, without departing from the spirit or sacrificing any of the 5 principles of the invention.

Having thus described the invention, what is claimed is:

1. In a garment, companion sections having adjoining edge portions folded inwardly back 10 upon themselves and sewed to each other at the fold line to form a seam and wide hems at opposite sides of the seam, and a gauge strip extending longitudinally of the seam against exposed faces of the hems with its transverse center 15 aligned with the seam, companion gauge markings being provided upon the strip at equal distances from the center whereby the hems may be accurately brought together and sewed to each other and the original seam removed to increase 20 the size of the garment.

2. In a garment, companion sections having adjoining edge portions folded inwardly and sewed to each other at the fold line to form a seam and hems along opposite sides thereof, lower portions 25 of the sections being turned up and secured to form a lower hem, and a gauge strip between the lower hem and side hems extending longitudinally of the side hems and having longitudinally extending gauge markings spaced equal distances 30 from the transverse center of the gauge strip whereby the side hems and companion gauge markings may be brought together and the side hems sewed together and the original seam removed to increase the size of the garment. 35

3. In a garment, sections having side edge portions sewed together to form a seam and wide hems at opposite sides thereof, and a strip extending along said hems in bridging relation thereto and having companion gauge marks spaced equal 40 distances from the seam whereby the hems may be folded to bring selected ones of the companion gauge marks together and the hems seamed to each other and the original seam removed to accurately increase the size of the garment. 45

4. A garment having a seam and free edge portions at opposite sides of the seam, and a strip secured in bridging relation to the seam and the said free edge portions, said strip having a medial line intermediate its width disposed in alignment 50 with said seam, companion gauge markings being provided at equal distances from opposite sides of said medial line to permit the said free edge portions to be equally adjusted and the size of the garment altered. 55

HARRY D. LYTTLE.
